[57] CLAIM

The ornamental design for a multicompartment container, as shown and described.

DESCRIPTION

FIG. 1 is a perspective view of a multicompartment container showing my new design, with a sliding lid in open position;

FIG. 2 is a top plan view thereof, with a sliding lid removed for clarity;

FIG. 3 is a bottom plan view thereof;

FIG. 4 is a front elevation thereof;

FIG. 5 is a rear elevation thereof;

FIG. 6 is a left side elevation thereof, the right side elevation being a mirror image;

FIG. 7 is a sectional elevation taken along line 7—7 of FIG. 2;

FIG. 8 is a sectional elevation taken along line 8—8 of FIG. 2; and,

FIG. 9 is a sectional elevation taken along line 9—9 of FIG. 2, with a sliding lid in closed position for clarity.
